Application February 14, 1935, Serial No. 55,435

Term of patent 3½ years

To all whom it may concern:

Be it known that I, Isidore Lending, a citizen of the United States, residing at New Bedford, in the county of Bristol, and State of Massachusetts, have invented a new, original, and ornamental Design for Hand Bags, of which the following is a specification, reference being had to the accompanying drawing, forming part thereof.

Figure 1 is a front view drawn on slightly larger scale of the hand bag showing my new design.

Figure 2 is a view of the hand bag with the surface ornamentation omitted in an upright posi-

tion showing one compartment of the hand bag.

Figure 3 is a view of the hand bag with the surface ornamentation omitted in an open position showing the other compartment open.

The back view of the hand bag is the same as Figure 1, with the exception that the flap on the rear of the bag is stitched, while in the front, it acts as a closing member.

I claim:

The ornamental design for a hand bag, as shown and described.

ISIDORE LENDING.
